PLATE GLUE SPREADER

Filed March 31, 1926

UNITED STATES PATENT OFFICE

HARRY G. FRANCIS, OF RUSHVILLE, INDIANA

PLATE GLUE SPREADER

Application filed March 31, 1926. Serial No. 98,710.

It is the object of my invention to produce a machine suitable for use in applying glue to boards, and particularly to the edges of boards.

I accomplish the above object by providing a glue pan in proximity to which I mount a movable plate adapted to be power-operated to dip periodically into the glue, to emerge therefrom, and to remain stationary for an interval to enable an operator to apply the boards to the glue-covered face of the plate.

The accompanying drawing illustrates my invention: Figs. 1 and 2 are end and side elevations respectively of my glue spreader showing the parts in position with the plate at rest, Fig. 2 being in partial section; Fig. 3 is a fragmental end elevation showing the parts in the position they occupy when the glue-spreading plate is midway of its passage through the glue; and Fig. 4 is a fragmental side elevation illustrating a modified form of mechanism for moving the glue-spreading plate.

By invention comprises a glue pan 10 partially surrounded by a steam jacket 11 which is supported from the floor as by the legs 12. Extending longitudinally above the center of the glue pan 10 is a rotatable shaft 13 upon which are rigidly mounted brackets 14 which support the glue-spreading plate 15. The shaft 13 is so arranged relative to the glue pan 10 that as the shaft is rotated the plate 15 will pass through the glue in the pan.

For the purpose of operating the plate 15, I prefer to employ some suitable source of motive power such as the electric motor 20 which is conveniently mounted upon a shelf 21 attached to the legs 12. The motor 20, through gears 22 and 23, drives a worm shaft 24 upon which is rigidly mounted a worm 25. The worm 25 meshes with a worm wheel 26 which is rigidly attached to a shaft 27 rotatably mounted in suitable bearings 28 and 29. The shaft 27 carries a gear 30 which meshes with a gear 31 rotatably mounted on a stud-shaft 32 which is conveniently supported from the steam jacket 11.

The gear 31 is connected to the shaft 13 by means which will impart an intermittent

motion to such shaft so that the plate will rotate through the glue in the pan 10 and will remain at rest for an interval in a substantially horizontal position above the glue. In Figs. 1, 2, and 3 the means for connecting the gear 31 with the shaft 13 is shown as consisting of intermittent gears 35 and 36, the gear 35 conveniently being rotatably mounted on the stud-shaft 32 and rigidly interconnected with the gear 31. A collar 37 may be applied to the stud-shaft to retain the gears 31 and 35 in position.

The intermittent gearing 35—36 is conveniently arranged to permit the plate 15 to remain stationary in a horizontal position above the glue through approximately two-thirds of the revolution of the gear 35. During the remaining one-third of the revolution of the gear 35, the plate 15 makes a complete revolution, in the course of which it passes through the glue in the pan 10.

This particular arrangement of rest and motion periods of the plate 15 is not essential, as the relative lengths of time in which the plate is moving and is stationary may be varied to suit operating conditions. It is not even necessary that the movement of the plate cease after every revolution, and it also is unnecessary, except as claimed, that stopping of plate movement be automatically effected. The arrangement described, in which the plate 15 automatically comes to rest after each revolution is, however, preferred.

During the interval in which the plate 15 is stationary, an operator may apply one or more boards A thereto as indicated in Figs. 1 and 2. Sufficient glue adheres to the plate 15 so that an adequate coating of glue may be thus applied to the edges of the board or boards. The periodic rotation of the plate 15 through the glue in the pan 10 keeps the glue agitated and of uniform quality throughout.

In Fig. 4 I have illustrated a modification of my device in which intermittent motion is applied to the shaft 13 by means of a clutch which is periodically released to permit the shaft 13 to remain stationary with the plate 15 in a horizontal position above the glue. In this construction a worm 40 is

mounted directly on the shaft of the electric motor 20 and meshes with a worm gear 41 carried by a shaft 42. The shaft 42 is rotatably supported in suitable bearings 43 and 44 and on such shaft there is rigidly mounted a pinion 45 which meshes with an idler gear 46 which is rotatably supported conveniently from the end of the steam jacket 11. The idler gear 46 meshes with a gear 47 which is rotatably mounted on the shaft 13.

10 The shaft 13 extends outwardly beyond the gear 47 and supports an axial slidable clutch member 48 which at its inner end is provided with a conical clutching surface complementary to a clutching surface in the adjacent end face of the gear 47. The clutch member 48 rotates with the shaft 13 and may be moved back and forth axially thereof by means of a clutch shifter 49 which extends 20 downward across the outer face of the idler gear 46 and is pivotally mounted at its lower end. A spring 51 acts between the clutch shifter 49 and any convenient stationary point and tends to hold the clutch member 25 48 in engagement with the gear 47.

Attached to the outer face of the idler gear 46 is an arcuate cam 52 which is adapted to bear against a cam roller 53 mounted on the clutch shifter 49. When the cam 52 and cam 30 roller 53 are in engagement, the clutch shifter 49 is moved to the left to disengage the clutch member 48 from the gear 47, and during the period of the engagement of the cam 52 and the cam roller 53 the shaft 13 remains 35 stationary with the plate 15 in the horizontal position illustrated in Fig. 4. The cam 52 conveniently has an extent of approximately 240 degrees in order that the plate 15 may remain stationary through two-thirds of the 40 revolution of the idler gear 46. During the remaining one-third of the revolution of the idler gear the shaft 13 makes a complete revolution to carry the plate 15 through the glue in the pan 10.

45 My invention is not limited to either of the particular means described for imparting an intermittent motion to the shaft 13 and plate 15, as the desired result can be accomplished in any convenient manner. In the modification of my invention illustrated in Figs. 1, 2, and 3, I have illustrated the worm 25 as mounted on an individual shaft, while in the construction shown in Fig. 4 the corresponding worm 40 is mounted directly on the shaft 50 of the motor 20. I prefer the former method of mounting, as in such a construction the end thrust incident to a worm drive is not imparted to the armature shaft of the motor 20.

55 60 I claim as my invention:

1. A device suitable for use in applying adhesive material to the faces of boards or the like, comprising an open-topped pan for containing a supply of the adhesive material, a substantially flat spreader plate pivotally

mounted on a horizontal axis above the level of the adhesive in the pan and adapted to dip into and emerge from the adhesive material as it rotates, and means for moving said plate intermittently about its axis to invert and dip it periodically into the adhesive material in said pan and to come to rest thereabove in a predetermined position such that articles may be applied to and removed from its adhesive-covered surface.

2. A device suitable for use in applying adhesive material to the faces of boards or the like, comprising an open-topped pan for containing a supply of the adhesive material, a substantially flat spreader plate pivotally mounted on a horizontal axis and adapted to dip into and emerge from the adhesive material as it rotates, and means for moving said plate intermittently about its axis to invert and dip it periodically into the adhesive material in said pan and to come to rest thereabove in a predetermined position such that articles may be applied to and removed from its adhesive-covered surface.

3. The invention set forth in claim 2 with the addition that said pan has a cylindrical bottom substantially concentric with the axis about which the plate moves.

In witness whereof, I have hereunto set my hand at Rushville, Indiana, this 27th day of March, A. D. one thousand nine hundred and twenty-six.

HARRY G. FRANCIS.
